UNITED STATES PATENT OFFICE.

JOHANNES VALDEMAR MÄRTEN RISBERG, OF SÖDERTELJE, SWEDEN, ASSIGNOR TO
AKTIEBOLAGET BALTIC-SEPARATOR, OF STOCKHOLM, SWEDEN.

LINER FOR CENTRIFUGAL LIQUID-SEPARATORS.

No. 902,913.

Specification of Letters Patent.

Patented Nov. 3, 1908.

Application filed February 16, 1906. Serial No. 301,490.

To all whom it may concern:

Be it known that I, JOHANNES VALDEMAR MÄRTEN RISBERG, a subject of the King of Sweden, residing at Södertelje, in the Kingdom of Sweden, have invented new and useful Improvements in Liners for Centrifugal Liquid-Separators, of which the following is a specification.

Among means used in centrifugal liquid separator drums for increasing the effect the most general one consists in funnel like plates, inserted into each other and dividing the contents of the drum (as for instance milk) into layers thin in radial direction in the well known manner. The skimming operation or the separating of the fatty globules from the milk serum is effected in the said thin milk layers in such manner, that the globules, being lighter than the said serum, are forced inward toward the center of the drum along the upper surface of the plates, while the heavier serum is forced outward toward the periphery of the drum owing to the continual supply of full milk to the drum. The separation of the fatty globules is effected more speedily the shorter the distance is between the plates, and it is possible, by providing sufficiently thin layers, to extract a great part of the very smallest fatty globules, difficult to separate owing to the comparatively great friction, to which they are subjected.

As learned from the practice, however, one may not proceed too far on this way, as the distance between the plates cannot be below a certain minimum without the effect being decreased, owing to the fact that the blue milk particles will run outward with such a great force, that they counteract by a friction the movement of the fatty globules in the opposite direction. This invention has for its object to reduce the friction-surfaces between the two liquid currents by a special construction of the conical plates, so that the distance between the plates can be reduced below the said minimum without the stronger liquid-currents, resulting therefrom, counteracting the movement of the fatty globules toward the center of the drum. Forces acting upon the fatty globules will move the same toward the center but not directly along the projection of the radius on the upper side of the plate, as one may think, but in a curved line, forming the resultant of two different forces, viz. the centrifugal

force acting along the radius vector, and the inertia of the fatty globules, acting in such manner, that the fatty globules, when moving inward toward the center, tend to retain the movement in the linear or peripheral direction, in which they were moving when in the starting-point of the inward motion. As the velocity in the peripheral direction is greater at the periphery of the drum than at points situated nearer to the center of the same, the fatty globules, moving toward the center, will have at each point a peripheral velocity, which, owing to their inertia, is greater than the actual peripheral velocity of each point, owing to which fact the globules do not follow the radius vector from the starting point but deviate from the said radius in the rotary direction, the deviation increasing toward the center in such a manner, that the globules are moving in a path more or less spiral in shape. In fact, however, the fatty globules are not able to perform the said movement in an undisturbed manner in liners consisting of conical plates of the construction hitherto used, which fact is substantially due to the continual supply of the full milk.

According to this invention the conical plates are so constructed, that the cream currents, owing to the said movement of the fatty globules, are directed to certain compartments, which are not disturbed by the full milk continually running into the liner.

In the accompanying drawings Figure 1 is a vertical section of a liner arranged in accordance with this invention (only a few plates are shown). Fig. 2 is a plan view of a plate. Fig. 3 is a vertical section of a modified form of the invention. Fig. 4 is a plan view of one of the plates shown in Fig. 3. Fig. 5 is a section on the line A—B of Fig. 3. Figs. 6 and 7 are plan views of two other modifications.

For the purpose stated above the plates are provided with radial interposed pieces a Figs. 1 and 2, extending from or substantially from the central opening of the plate to the periphery, consequently over the whole skimming surface. x, Fig. 2, may indicate a fatty globule, which is on the point of being separated from a milk layer between the plates. The said globule is forced toward the center owing to the centrifugal force acting upon the milk, but as the said globule acted upon by its inertia at the same

time tends to retain a peripheral velocity, which is greater than that of the neighboring parts of the plate, as stated above, the globule will move in the direction indicated by the arrow at x , provided that the drum is rotated clockwise. Owing to this fact the globules will gather at the rear side b of the pieces or ribs a and move along the same inward toward the center.

10 The blue milk particles, on the other hand, are also subjected to the action of the centrifugal force and the inertia. The centrifugal force forces the same outward toward the periphery, owing to their greater specific weight, and owing to their inertia they tend to retain their initial peripheral velocity. As the said particles are moving from points with less peripheral velocity toward points with greater velocity, they will, contrary to 15 the fatty globules, slide backward on the plates and consequently move in a direction opposite to that of the fatty globules *i. e.* opposite to that indicated by the arrow at x . Owing to this fact a current of blue milk will 20 move toward the periphery along the front side d of the ribs a . Consequently, the spaces between the plates are divided by the ribs into compartments, some ones for the cream and other ones for the blue milk. In 25 order to avoid collision between the cream currents and the full milk entering the liner, the latter is led into the spaces between the plates through openings e , provided in the parts of the neutral zone, which are situated 30 just in front of the ribs a with regard to the rotary direction. Owing to currents caused by the ribs the neutral zone, which in liners before known consists of a cylindrical layer will have the shape indicated by the dotted 35 lines c . Consequently the full milk is introduced at points of the neutral zone situated nearest to the center. The distance of the neutral zone from the center, however, changes owing to certain variable agents and 40 for that reason the openings e must be made 45

sufficiently great radially and may, advantageously, have the same length as the ribs a . In such case the plates are preferably arranged as shown in Figs. 3 and 4. The plate strips f resulting from the providing of 50 the openings e are folded along the edges, cohering with the plate cone, outward or inward in such a manner, that they bear against the outer or inner side respectively of the cone and form the ribs or interposed 55 pieces a , as shown in Fig. 5.

The interposed pieces or ribs a may be provided in many other ways as for instance by projections formed in the plate by pressing, as readily understood by those skilled in 60 the art. The ribs may have other directions than the radial one without their action being substantially changed. Thus in Figs. 6 and 7 plates are shown having ribs a extending in an oblique or spiral direction. 65

Having now described my invention, what I claim as new and desire to secure by Letters Patent is:

In liners for centrifugal separators, the combination with conical plates arranged 70 one within the other, of ribs a extending substantially from the central openings of the plates toward their peripheries and located substantially above the ribs of the next subjacent plate through the whole set of plates 75 and having a height equal to the distance between the plates, so that the spaces between the plates are divided into separated cells, and inlet openings e for the said cells, located immediately in front of the ribs forming 80 the rear partition walls of the cells with relation to the rotary direction.

In testimony whereof I have signed my name to this specification in the presence of two subscribing witnesses.

JOHANNES VALDEMAR MÄRTEN RISBERG.
